NONREFILLABLE RECEPTACLE

Frank A. Talbot, Baltimore, Md., assignor of one-half to William B. W. Mann, Towson, Md.

Original application September 25, 1931, Serial No. 565,155. Divided and this application November 21, 1932, Serial No. 643,708

13-Claims. (Cl. 220—86)

This invention relates to improvements in receptacles of the type to be used only once, that is, of the kind which cannot be refilled, and the present application is a division of my application Serial No. 565,155, filed September 25th, 1931, on which Patent No. 1,890,421 was granted Dec. 6, 1932.

The primary object of the invention is to furnish improved liquid and air passageways combined with suitable baffle means and a valve, all so constructed that the device may be manufactured at relatively small expense, and which will be practical and durable in action.

Another object is to provide a receptacle of the non-refillable type, in which the valve which prevents refilling, is initially held off its seat by a suitable retainer, said retainer when the closing plug of the receptacle is inserted, functioning to release the valve retaining means, whereby the valve automatically seats, when the closure plug is attached to the receptacle.

A further object is to furnish a device of this character, in which the valve may be initially held off its seat by magnetically operated means, such means, when actuated by a magnet, functioning to move out of obstructing position so that the valve may automatically close.

A still further object is to provide a device of this kind, having the valve initially held off its seat by distortable pins or the like, which may be distorted by movement of the passageway baffle, the latter being actuated either by magnetic or mechanical means.

A further object is to provide such structures with means to facilitate their attachment to the conventional pump used at the top of an oil dispensing drum or the like, whereby as the liquid is pumped from the drum or barrel, air may enter the latter through the pump to displace the oil discharged.

With the foregoing objects outlined and with other objects in view which will appear as the description proceeds, the invention consists in the novel features hereinafter described in detail, illustrated in the accompanying drawings, and more particularly pointed out in the appended claims.

In the drawings,

Fig. 1 is a vertical sectional view of one form of the device, as employed in connection with a non-refillable drum.

Fig. 2 is a horizontal sectional view of the same on the line 2—2 of Fig. 1.

Fig. 3 is a vertical sectional view of a modification.

Fig. 4 is a similar view of another modification, and with the top ring removed to facilitate illustration.

Fig. 5 is a horizontal sectional view on the line 5—5 of Fig. 4.

Fig. 6 is a vertical sectional view of a portion of an oil drum and a dispensing pump, and illustrating an adapter by which the conventional pump may be used with any one of the forms of my invention disclosed herein.

Fig. 7 is a top plan view of the top ring of any one of the forms of the invention illustrated.

In the embodiment of the invention illustrated in Figs. 1 and 2, 8 designates the shell of the improved structure which may be shaped at its bottom as shown at 9, to be connected to the down pipe 10 which extends from the top to the bottom of an oil drum. In forming the shell from sheet metal, it is preferably provided with an annular trough, as shown at 11, for a purpose hereinafter described.

The upper end of the shell is crimped, as shown at 12, to an annular ledge 13 which is positioned below the extreme upper surface 14 of the top ring 15 of the device, so that channels or grooves 16 radially placed in said upper surface will function to admit air to the drum beneath the head 17 of the latter, while oil is being withdrawn from the drum.

In accordance with the invention, the top port 25 of the ring 15, as best shown in Fig. 7, is preferably of octagonal shape, as indicated at 18, and this specially shaped aperture has its wall undercut or recessed as at 19 in Fig. 1. This permits the sheet metal forming the head of the drum 30 to be crimped about four sides of the octagonal wall and into the recess, but on the other four alternate sides of such wall, where the channels or grooves 16 are placed, the metal can be left uncrimped, so that air may enter the octagonal 35 opening and pass into the drum through the channels 16. In other words, the connection between the ring 15 and the top of the drum is such that while the ring is securely held in place, the bent edge of the metal of the top does not 40 obstruct the air passageways 16.

An inverted annular channel or trough 20 is positioned in the under side of the top ring 15, and as best shown in Fig. 3, upwardly extending arms 21 of a cup-shaped baffle 22 extend into the upper channel while legs 23 of the same baffle project into the trough 11. This arrangement enables the baffle to be rigidly secured to the shell and top ring, as will be the case in the construction shown in Figs. 1, 2 and 3, or to 45 rotate within the shell, as will be explained in connection with Figs. 4, 5 and 6.

In each form of the invention there is a valve employed to close the lower end of the shell to prevent refilling of the receptacle, but the valve 55 in the beginning is retained in open position so that the vessel may be filled through the top ring 15, and the inflowing liquid will flow between the arms 21 of the baffle, then through the annular space 24 between the baffle and shell, and thence 60

between the legs 23, and finally through the bottom opening of the shell.

This valve is designated 25 in Fig. 1, 25a in Fig. 3, and 25c in Figs. 4, 5 and 6.

5 The means for initially retaining the valve in open position in Figs. 1 and 2 consist of a resilient metal yoke or inverted U-shaped member 26 which extends diametrically across the cup forming the baffle, and has hook legs 27 which 10 extend beneath the valve 25 so as to normally prevent a spring 28 from forcing the valve on to its seat 29.

15 The closing plug 30 for the drum, is employed to actuate this valve retainer, and it will be observed that for this purpose, the threaded skirt 31 is slightly longer than usual, whereby when the plug is screwed into the threaded portion 32 of the top ring, its skirt will move the diametrical portion of the retainer downwardly as indicated 20 in dotted lines, whereby the hook legs will be removed from beneath the valve and the spring 28 will force the latter to its seat.

From this it will be understood that while the receptacle is being initially filled, the retainer 25 will prevent the valve from closing, but when the sealing plug 30 is attached, it will function to move the retainer so that the latter will release the valve and the valve will seat. From that 30 time on, the spring 28 will seal the device against refilling, but of course, the spring has insufficient strength to prevent liquid from flowing outwardly when it is pumped in the usual way.

It is preferred that a gasket 33 be used in connection with the plug 30 to close any exit from the air grooves 16 to prevent any outward seepage of oil through these grooves while the receptacle is in transit.

If preferred, as shown in Fig. 3, the valve 25a may be initially held off its seat by a bow spring 40 26a which is positioned beneath the valve and has legs 27a resting on the lower portion of the shell. In this case, the valve will be spaced slightly from the bottom 22a of the baffle, and will be formed of magnetic material, and when 45 magnetic force is exerted upwardly through the opening in the top of the device, the valve 25a will rise slightly and the legs 27a, under their own resiliency, will spring toward one another so that the retainer 26a will drop into the pipe 10a, and then the spring 28a will force the valve to its 50 seat, when the magnetic force is released.

As shown in Figs. 4 to 6 inclusive, the valve can be initially retained off its seat by distortable arms or pins 40 which project inwardly from the 55 wall of the shell and initially support the valve 25c. In this event, the baffle 22b will be rotatably arranged within the shell, and consequently, when the baffle is rotated about the axis of the shell, its legs 23a will strike the pins and bend the same out of valve obstructing position, as indicated in Fig. 5. Then the spring 28b will act to seat the valve.

The baffle in this instance can be rotated by any suitable magnetic tool inserted through the 60 top of the device, or the baffle may have its cylindrical wall provided with inwardly pressed protrusions 22c that may be engaged by any special turning tool built for the purpose.

As illustrated in Fig. 6, any of the forms of 70 the device described may be employed in connection with a conventional suction pump provided the latter is equipped with an improved adapter. As illustrated in this figure, a conventional pump 50 has a suction pipe 51, and this 75 pipe is provided at its lower end with a nut 52

that is externally threaded so that it may be screwed into the threaded portion 32 of the top ring. Another threaded collar 53 is secured to the base portion of the pump and bears on the sealing gasket 33, after the sealing plug is 5 removed. With this arrangement, the external passageway 54 of the pump communicates by way of the grooves 16 shown in Fig. 7 with the interior of the receptacle, so that air may flow through the pump into the receptacle while oil is 10 withdrawn from the latter through the pipe 10 and past the valve 25c.

In all of my constructions, as the valve 25, 25a, 25c is supported by the shell or cup 8 secured to the top 17 of the drum, the down pipe 15 10, 10a may be made of a thin tin tube which may be of inexpensive and light construction. Furthermore, the arrangement of the valve at the top of the drum eliminates the necessity of employing a suction valve in the pump, as my 20 valve is arranged sufficiently close to the pump to serve as a suction valve for the same. Moreover, as the down tube does not have to carry a valve, and therefore may be made of light material, it is unnecessary to anchor its lower 25 end to the bottom of the drum where it extends into the sump, (Fig. 6).

In the last mentioned figure, the construction is also such that the pump may face in any direction relatively to the drum. As advertising matter is usually placed at one side of such a drum, it is desirable that the pump face in that direction. In accordance with my invention, the member 52 can be screwed downwardly to a desired depth within the ring 32, and then the 35 pump may be turned to face the pump in the desired direction. Afterwards, the nut 53 can be screwed down on to the gasket 33 to make a tight joint and to prevent the pump from accidentally moving out of proper position relatively 40 to the advertising matter on the drum. In other words, my parts 51, 52 and 53 are of such construction relatively to the drum, that they in effect form a swivel connection for securing the 45 pump to the drum.

From the foregoing it is believed that the various forms of the invention which have been illustrated may be clearly understood, and it is manifest that changes may be made in the details disclosed, without departing from the spirit 50 of the invention, as expressed in the claims.

What is claimed and desired to be secured by Letters Patent is:

1. A non-refillable receptacle comprising a tubular shell, a valve in the shell for preventing 55 refilling of the vessel through said shell, a baffle in the shell for preventing the valve from being opened after it once has been closed, and means cooperating with the valve and having sufficient rigidity to initially prevent the valve from seating, said means being operable from the exterior of the receptacle and adapted to permanently remain in the receptacle after the valve has been seated.

2. A non-refillable receptacle comprising a 65 tubular shell, a valve in the shell for preventing refilling of the receptacle through said shell, a baffle in the shell for preventing the valve from being opened after it once has been closed, and means cooperating with the valve and having 70 sufficient rigidity to initially prevent the valve from seating, said means being operable from the exterior of the receptacle and adapted to permanently remain in the receptacle after the valve has been seated, said baffle being of cup 75

shape and provided with upwardly extending arms and downwardly extending legs, and also having a cylindrical wall spaced from the wall of the shell.

5. 3. A non-refillable receptacle comprising a tubular shell, a valve in the shell for preventing refilling of the receptacle through said shell, a baffle in the shell for preventing the valve from being opened after it once has been closed, means cooperating with the valve and having sufficient rigidity to initially prevent the valve from seating, said means being operable from the exterior of the receptacle after the valve has been seated, and a spring for forcing the valve toward its seat.

4. A non-refillable receptacle comprising a tubular shell having a bushing, a valve in the shell for preventing refilling of the receptacle through said shell, a baffle in the shell for preventing the valve from being opened after it once has been closed, retaining means cooperating with the valve and having sufficient rigidity to initially prevent the valve from seating, said retaining means being operable from the exterior 25 of the receptacle and adapted to permanently remain in the receptacle after the valve has been seated, and a sealing plug cooperating with the bushing and adapted to move the valve retaining means from obstructing position.

5. A non-refillable receptacle comprising a tubular shell, a valve in the shell for preventing refilling of the receptacle through said shell, a baffle in the shell for preventing the valve from being opened after it once has been closed, and means cooperating with the valve and having sufficient rigidity to initially prevent the valve from seating, said means being operable from the exterior of the receptacle and adapted to permanently remain in the receptacle after the valve has been seated, the means for initially holding the valve in open position comprising a strip extending across the baffle and having hook-shaped legs engaging the valve.

6. In a non-refillable receptacle, a passageway, a valve in the passageway for preventing refilling of the receptacle through the passageway, baffle means in the passageway for preventing the valve from being held off its seat during any refilling of the receptacle, a removable plug for closing the outer end of said passageway after the receptacle has been originally filled, and means actuated by said plug for releasably holding the valve off its seat during the initial filling of the receptacle, the plug functioning to cause the holding means to release the valve when said passageway is sealed by the plug.

7. In a non-refillable receptacle, a passageway, a valve for preventing refilling of the receptacle through said passageway, baffle means in the passageway for preventing tampering with the valve after it has once been seated, and magnetically operated means for initially holding the valve off its seat during the original filling of the receptacle, the last mentioned means comprising a strip arranged beneath the valve and cooperating with the valve and the wall of said passageway, the strip having sufficient rigidity to hold the valve off its seat until said strip is magnetically operated.

8. In a non-refillable receptacle, a passageway, a valve in the passageway for closing the latter when any attempt is made to refill the receptacle through said passageway, baffle means movably mounted in the passageway for preventing tam-

pering with the valve, and means for initially holding the valve off its seat, the baffle means being operatively connected to the last mentioned means for actuating the latter when the baffle means is moved.

9. In a non-refillable receptacle, a passageway, a valve in the passageway for closing the latter when any attempt is made to refill the receptacle through said passageway, baffle means movably mounted in the passageway for preventing tampering with the valve, and means for initially holding the valve off its seat, the baffle means being operatively connected to the last mentioned means for actuating the latter when the baffle means is moved, the baffle means being rotatably mounted in the passageway, and a spring for forcing the valve to its seat after it has been released.

10. In a non-refillable receptacle, a passageway, a valve in the passageway for closing the latter when any attempt is made to refill the receptacle through said passageway, baffle means movably mounted in the passageway for preventing tampering with the valve, and means for initially holding the valve off its seat, the baffle means being operatively connected to the last 25 mentioned means for actuating the latter when the baffle means is moved, the means for holding the valve off its seat including distortable elements actuated by the baffle means when the latter is moved.

11. In a non-refillable receptacle, a passageway, a valve in the passageway for closing the latter when any attempt is made to refill the receptacle through said passageway, baffle means movably mounted in the passageway for preventing tampering with the valve, and means for initially holding the valve off its seat, the means for holding the valve off its seat including distortable pins projecting inwardly from the wall of the passageway, the baffle means being rotatable 40 and having spaced projections adapted to bend the pins out of obstructing position when the valve is rotated.

12. In a device of the character described, a receptacle having a passageway, a top ring forming part of said passageway, a top for the receptacle rigidly secured to said ring, said ring being threaded, a pump having a suction pipe having a threaded connection with the threaded portion of the ring, and an air inlet pipe surrounding the 50 suction pipe and having one of its ends impinging against the top in a circle coinciding with said ring, and air grooves in the ring placing the interior of the air pipe in communication with the interior of said receptacle.

13. In a device of the character described, a receptacle having a top, a hollow cup rigidly secured to the top of the receptacle, a down tube rigidly connected to the cup and extending downwardly in to close proximity to the bottom of the drum, a ring secured to the top of the receptacle where the cup is located, said ring, cup and down tube forming a passageway from the bottom to the top of the receptacle, a check valve arranged in said cup above the down tube and closing the latter against filling with liquid introduced through said ring, a pump removably mounted on the top of the receptacle and having a threaded connection with said ring, and a nut having a threaded connection with the pump and bearing 65 against the top of the receptacle for securing the pump in position.

FRANK A. TALBOT.
